CARBURETORS

Milton E. Chandler, New Britain, Conn., assignor, by
mesne assignments, to Pratt & Whitney Company, In-
corporated, West Hartford, Conn., a corporation of
Delaware

Application February 29, 1952, Serial No. 274,185

8 Claims. (Cl. 261—39)

This invention pertains to carburetors for internal combustion engines of the type shown in U. S. Patent No. 2,432,274, issued December 9, 1947, and more particularly has reference to means for regulating the fuel-to-air ratio in the idling range of the engine.

In carburetors of the type mentioned, the fuel flow is controlled by an orifice, fixed in size during part of the operating range, but varied manually in the idling range and automatically in the higher power range of the engine. The metering head across the orifice is controlled by a valve which is actuated by balancing the pressure differential of the air flowing through the main air passage, against the pressure differential of the fuel flowing through the metering jet system, of the carburetor. At low air flows which obtain under idling conditions, the air pressure differential set up in the main air passage becomes so weak and erratic as to not constitute a reliable means for regulating the fuel flow, in accordance with the principle of balancing air flow pressure differential against fuel flow pressure differential. In order to overcome this difficulty, it has heretofore been customary to provide a spring which biases the fuel valve, in opposition to fuel flow differential, and becomes the controlling force acting of said valve at the low fuel flows which occur during idling operation of the engine. The fuel flow pressure differential is held approximately constant by said spring and the rate of fuel flow under idling conditions is regulated by an idle valve which is connected to the main throttle valve of the carburetor, so as to vary the opening of the idle valve in accordance with the position of the throttle valve, in the idling range of the engine, as is disclosed in U. S. Patent No. 2,432,274, cited above.

While such an arrangement improved the idling operation of the carburetor over previous constructions, it is attended with certain inherent disadvantages and limitations which cause a lack of stability and repeatability in the metering of the fuel at idling air flows. This is due primarily to the fact that, in carburetors of the type mentioned above, the main fuel valve is basically a pressure reducing valve which varies the unmetered fuel pressure as a function of air flow, and has to control fuel flows which vary from a minimum of about 25 pounds per hour (idling) to a maximum of about 2500 pounds per hour. This is a ratio of variation of approximately 100 to 1—an extremely wide range of operation for precise control, even where all the forces involved are steady. Since the main fuel valve must be made large enough to pass the maximum fuel flow required for the maximum power output of the engine, it has a certain inherent inertia and friction which reduce its ability to move with sufficient precision and steadiness to satisfactorily control the relatively small fuel flows required for idling operation. Because of these difficulties, which are inherent in any carburetor wherein the main fuel valve is employed as one of the elements to control the idle fuel flow, such carburetors have proven incapable of maintaining the

2

stability and repeatability of idle fuel metering that is now demanded for satisfactory engine operation.

In addition to the foregoing inadequacies of prior art carburetors to meet present requirements of stability and repeatability of fuel metering under idling conditions, it has been found desirable in aircraft carburetors to vary the idling fuel/air mixture in accordance with engine temperature and barometric pressure, in order to obtain the best engine operation when the aircraft is flying at varying altitudes and when coming in for a landing. Since aircraft carburetors heretofore in use provide an idling fuel/air mixture, based only on normal engine operating temperatures and under air pressure differentials that occur at sea level barometric pressures, such carburetors are incapable of giving the desired idling fuel/air mixtures at other engine temperatures and flight altitudes.

An object of this invention is to improve carburetor operation under idling conditions by providing an additional, very small, fuel pressure regulating valve, in parallel with the main fuel pressure regulating valve, and arranged so that it maintains during idling operation a substantially constant fuel metering head in excess of that which would be produced by the main valve acting alone, or a metering head that is a maximum at the lowest idling fuel flow and decreases with increase in idling fuel flow in a selected manner, so as to blend with the metering head of the main fuel flow at the point of maximum idling fuel flow.

Another object is to provide a carburetor in which the fuel metering head, during the idling regime, is held substantially constant, or is varied in a selected manner, by a very small fuel pressure, regulating valve in parallel with a main fuel pressure regulating valve, and the idling fuel flow is controlled by a throttle-operated, idle fuel valve in the conventional manner; and when the air flow through the carburetor requires a fuel metering head in excess of that produced by the small parallel valve, said valve will close and the main fuel regulating valve will take over the fuel metering in the normal manner.

Still another object is to provide a carburetor wherein the idling fuel/air mixture is varied in accordance with engine temperature and/or barometric pressure.

With these and other objects in view, which may be incident to my improvements, my invention consists in the combination and arrangement of elements hereinafter described and illustrated in the accompanying drawings, in which:

Figure 1 shows, somewhat diagrammatically, a carburetor for an aircraft type internal combustion engine, including an idling mixture control system constructed in accordance with my invention;

Figure 2, is a view, similar to Figure 1, of a modified form of my invention wherein the idle fuel/air mixture is varied in accordance with engine temperature and barometric pressure; and

Figure 3 is a graphical illustration of the idling fuel/air metering characteristics which are obtained with the carburetors shown in Figures 1 and 2.

In Figures 1 and 2, elements of the carburetor which are the same in both species are indicated by the same reference numeral.

Figure 1

Referring first to Figure 1, there is shown a carburetor body 10 through which air flows from an entrance 12, past a venturi 14, a throttle 16 and a fuel discharge nozzle 18 to a mixture outlet 20. The mixture passes from the outlet 20 to the engine. In most cases, a supercharger is used between the outlet 20 and the engine. In some cases a second supercharger is used upstream from the entrance 12.

Air flowing through the venturi 14 creates an air pres-

sure differential between the entrance and throat of the venturi, which differential varies with the velocity of the air flowing. This air pressure differential is utilized to create a flow of air through a secondary air conduit connecting the entrance and throat of the venturi. A plurality of impact tubes 22 are provided in the entrance 12, with their ends open to receive the impact of the entering air. Air flowing through the secondary conduit just mentioned enters these impact tubes 22 and passes to a common passage 24, usually termed a vent ring. From the vent ring 24, the air flows through a conduit 26, a chamber 28 in a fuel meter generally indicated at 30, a fixed restriction 32, an expandible chamber 34 in the fuel meter 30, a conduit 36, past a valve 38 into a chamber 40, and thence through a conduit 42 to the throat of venturi 14.

Valve 38 is positioned by a bellows 44 located in the chamber 40. The bellows 44 is sealed so as to expand and contract with variations in pressure in chamber 40. The bellows 44 is preferably partially filled with nitrogen or other suitable fluid having an appreciable coefficient of thermal expansion, so that it also expands and contracts with variations in the air temperature. Since the bellows 44 responds to both temperature and pressure, it may be said to respond to air density. The valve 38 is contoured with relation to the response characteristics of the bellows 44 so that the pressure differential appearing across the fixed restriction 32 in the fuel meter 30 is an accurate measure of the mass rate of air flow passing through the venturi. In other words, the bellows operated valve 38 compensates for changes in density of the air passing through the venturi.

Fuel enters the carburetor from a pump (not shown) and flows through a conduit 50, past a valve 52 and expandible chamber 53 in the fuel meter 30, through a conduit 54, to a mixture control 56 including a disc valve 58 fixed on a shaft 60. From the mixture control 56, the fuel flows through one or both of a pair of parallel conduits 62 and 64 into a jet system 66. From the jet system 66, the fuel flows through an idle valve 68, a conduit 70, a pressure regulator 72 and a conduit 74 to the fuel discharge nozzle 18.

The fuel meter 30 includes a chamber 76 in addition to the expandible chambers 28, 34 and 53 previously described. Chambers 76 and 28 are separated by a flexible diaphragm 78, chambers 28 and 34 are separated by a flexible diaphragm 80; and chambers 34 and 53 are separated by a flexible diaphragm 82. The three diaphragms 78, 80 and 82 are attached at their centers to the stem of the valve 52, which is balanced against inlet pressure. Chamber 76 is connected through a conduit 84 to the conduit 70 in the fuel line on the downstream side of the jet system 66. Chamber 53 is, of course, supplied with fuel at the pressure existing on the upstream side of the jet system. It may, therefore, be seen that the valve 52 is positioned in accordance with the balance between a downwardly acting force which is a measure of the rate of flow of air to the engine, and an upwardly acting force which is a measure of the rate of flow of fuel to the engine. The downwardly acting force is the difference between the pressures in chambers 28 and 34, which difference is applied to the diaphragm 80. The upwardly acting force is the difference between the pressures in chambers 53 and 76, which is the fuel pressure differential across the jet system. Whenever the fuel flow is disproportionate with respect to the air flow, the valve 52 is moved to correct the fuel flow and maintain the same fuel-to-air ratio as before. The foregoing statement, with respect to the constant fuel-air ratio, assumes that the cross-sectional area in the jet system open to the flow of fuel therethrough is a constant. This, however, is not strictly constant, but is varied manually and automatically under certain conditions.

Fuel entering the jet system 66 through conduit 62

75

may pass through a restriction 86 directly to the outlet of the jet system. It may also pass through a passage 88 controlled by an enrichment valve 90 biased to closed position by a spring 92. Fuel passing through the conduit 64 flows through a fixed restriction 94. The opening movement of valve 90 is limited by a stop 96.

When the disc valve 58 of the mixture control 56 is in the position shown in full lines in the drawing, which is termed the "lean" position, fuel may enter the jet system only through the conduit 62. With the valve 58 in its "rich" position, as shown in dotted lines on the drawing, fuel may enter the jet system through both conduits 62 and 64.

When the valve 58 is in its lean position, a first predetermined relationship is established between the fuel pressure differential across the jet system and the rate of flow of fuel. When the valve 58 is in its rich position, a second such relationship is established, such that a greater fuel flow is obtained for each value of fuel pressure differential. Since the fuel meter 30 establishes a fixed relationship between the mass air flow and the fuel pressure differential, it may be seen that movement of valve 58 between its "lean" and "rich" positions selects respectively smaller and greater fuel-air ratios.

The enrichment valve 90 opens under high fuel pressure differential conditions, which correspond generally to conditions of high power output, to increase the fuel-air ratio. It should be noted that the operation of valve 90 is the same whether the mixture control is in its lean or rich position. The stop 94 limits the enrichment effect which is produced by valve 90.

The idle valve mechanism 68 includes a valve member 102 movable by means of an arm 104 connected through a link 106 to an arm 108 on the shaft 110 of the throttle 16. A spring 112 in fuel meter 30 biases the valve 52 toward open position, in opposition to a spring 114 which biases said valve toward closed position. These springs and valve 102 cooperate with an idle fuel pressure regulating valve mechanism 130 (described hereinbelow) to control the fuel flow to the engine under conditions of light load.

The pressure regulator 72 is provided to prevent variations in pressure at the fuel nozzle 18 from affecting the flow through the jet system. The regulator 72 includes a valve 116 biased to closed position by a spring 118. A diaphragm 120 separates a pair of expandible chambers 122 and 124. The chamber 124 receives fuel at the pressure on the downstream side of the jet system, while chamber 122 is vented to vent ring 24 through conduit 126 and conduit 26. The effect of this arrangement is to maintain a substantially constant pressure on the downstream side of the jet system.

Idle fuel pressure regulating valve mechanism 130 comprises a casing 132, divided by a flexible diaphragm 134 into two expandible chambers 136 and 138, of which the former is connected by a conduit 140 to chamber 76, and the latter is connected by a conduit 142 to chamber 53, in fuel meter 30. Fixedly mounted in casing 132 is a sleeve 144 which is provided with a sleeve valve 146, attached at its left end to diaphragm 134. A port 148 in sleeve valve 146 is adapted to varying the opening of a port 150 (in sleeve 144) which is connected to fuel inlet conduit 50 by a conduit 152 having a restriction 154. A spring 156 interposed between diaphragm 134 and the left end wall of casing 132 biases valve 146 toward open position, in opposition to the fuel pressure differential, acting on diaphragm 134, which consists of the difference between the unmetered fuel pressure p_2 , transmitted from chamber 53 to chamber 138, and the metered fuel pressure p_3 , transmitted from chamber 76 to chamber 136.

When the thrust of the fuel pressure differential $p_2 - p_3$ on diaphragm 134 is greater than the force of spring 156, valve 146 is moved to the left, closing port 150, which reduces the flow of fuel (under inlet pressure p_1)

from fuel inlet 50, through conduit 142 into chamber 53, and from thence through conduit 54, jet system 66, idle valve 102, pressure regulator 72 and conduit 74 to discharge nozzle 18. This reduction of fuel flow into chamber 53 tends to lower the pressure p_2 therein and in chamber 138, and such decrease in pressure (acting on diaphragm 134), causes spring 156 to move valve 146 to the right, thereby increasing the opening of port 150, and raising the pressure p_2 in chambers 138 and 53. Accordingly, as long as main fuel valve 52 remains closed, the fuel pressure upstream of idle valve 68 is held substantially constant, or may be varied in a selected manner, by the operation of valve 146. Since the metered fuel pressure p_s , downstream of idle valve 102, is held substantially constant by pressure regulator 72, the metering head across idle valve 102 may be held substantially constant, and the rate of fuel flow to the engine is proportional to the opening of contoured idle fuel valve 102, which in turn is proportional to the opening of the throttle 16 in the idling range.

In a carburetor, such as described above, the fuel flow is proportional to the square root of the metering head $p_2 - p_s$ which is a straight line function of the air flow through the carburetor, as indicated by line A in Figure 3. In the idling range of engine operation, which lies in the region of from 0 to 10 percent of maximum air and fuel flow, the air pressure differential set up by venturi 14 becomes very small and erratic (unsteady), so that it is no longer an accurate measure of the air flow. Therefore, in order to obtain an approximately constant metering head across the idle fuel valve, it has heretofore been customary to employ a spring (such as 112 in Figure 1) with a setting such that it controls the main fuel valve (such as 52 in Figure 1), when the air pressure differential becomes so weak that its action on said valve is uncertain, as in the idling range. While such an arrangement improves the idle metering head, it does not control it with a sufficient degree of accuracy and reliability to uniformly produce satisfactory idling operation of the engine, owing to the inertia and extremely small movements of the main fuel valve under idling conditions.

To overcome this difficulty I provide a very small, fuel pressure regulating valve 146, in parallel with the main fuel regulating valve 52, and arranged so that it maintains (during idling operation) an idle fuel metering head across the idle valve 102 in excess of that which would be produced by the main fuel valve 52 acting alone. To this end, springs 112 and 114 are adjusted so that when the air flow reaches a selected point, corresponding to the upper limit of the idling range (indicated at "O" in Figure 3), main fuel valve 52 closes, and sleeve valve 146 opens. Conversely, when the rate of air flow increases beyond the upper limit of the idling range, valve 146 closes port 150, and main fuel valve commences to open, thus taking over the regulation of the fuel pressure metering head across jet system 66.

When main fuel valve is closed and valve 146 is open, the fuel pressure upstream of idle valve 102 is held at a substantially constant or selected variable value which is determined by the rate and setting of spring 156 which is set to produce a metering head across idle valve 102 higher than that which would be produced by main fuel valve 52 if it were acting alone. Thus, if optimum idling operation of the engine is obtained by a fuel/air mixture resulting from a rate of fuel flow of say 200 pounds per hour (equal to 8 percent of maximum fuel and air flow), springs 112 and 114 are set so as to close main fuel valve 52 when the air flow is reduced to 8 percent of its maximum. Then spring 156 is set so as to cause valve 146 to produce a metering head across idle valve 102 such as to obtain a fuel flow of 200 pounds per hour at that point (indicated by O in Figure 3). Within the idling range, the pressure p_2 upstream of idle fuel valve 102 may be held substantially constant by the operation of valve 146, or said pressure may be varied,

so as to attain a maximum value at the lowest idling fuel flow and decrease with increase in idling fuel flow in a selected manner, such as to blend with the metering head of the main fuel flow at the point of maximum idling fuel flow, as indicated by the line B in Figure 3. Within the idling range, the rate of fuel flow is controlled by the pressure p_2 upstream of contoured idle valve 102, and the movement of said valve which is proportional to the movement of throttle 16.

10 Since valve 146 is relatively very small, in comparison with main fuel valve, and is actuated by a relatively large diaphragm through a large operating range, this valve is highly sensitive and responds quickly and accurately to variations in fuel pressure differential $p_2 - p_s$ and thereby holds said pressure differential extremely close to the selected value. Another factor which adds to the steadiness and accuracy of operation of valve 146 is that it is not subject to fluctuations in air pressure differential, as is main fuel valve 52, even during the 15 idling region, in prior art carburetors. While the fluctuations of air pressure differential in the idling range are small in comparison in the force of the spring (such as 112) which controls the main fuel valve 52 during idling operation, they are appreciable and tend to upset 20 the steadiness of the main fuel valve and thus adversely affect close control of the idle fuel flow.

25 From what has been disclosed above, it is apparent that the construction shown in Figure 1 provides a simple and very effective means of obtaining a close, stable and accurate control of the fuel flow in the idling regime.

Figure 2

Recent experience in the operation of aircraft has shown that, aside from accuracy and stability under idling 35 conditions, a constant fuel/air mixture does not meet all requirements in the idling operation of the engine. Thus, when flying at altitude or when coming in for a landing the pressure drops in the carburetor and the cylinder head temperatures of the engine are different. Hence, good 40 idling engine operation requires a different idling mixture. Since prior art carburetors can only give an idling mixture based on engine requirements when the engine is up to normal temperature, and under carburetor pressure drops that occur at sea level, such carburetors are incapable of meeting present requirements which demand 45 that the idling mixture be varied in accordance with engine cylinder head temperature and barometric pressure. To meet this demand, I have provided a modified form of my invention, as illustrated in Figure 2.

50 Since most of the elements of the carburetor shown in Figure 2 are the same as in the carburetor shown in Figure 1, and are indicated by the same reference numerals, these elements will not be further described. Referring to Figure 2, it will be noted that the carburetor here 55 illustrated differs from that shown in Figure 1, only in the additional mechanism that is added to the idle fuel pressure regulating mechanism 130, in order to make it responsive to engine cylinder head temperature and barometric pressure.

60 In the construction shown in Figure 2, the left end of casing 132 is provided with a cylindrical extension 160 in which is slidably mounted a cup piston 162 which forms the outer support for spring 156. Bearing against the outer face of piston 162 is the upper end of a lever 65 164, centrally pivoted to a fixed support 166, and having its lower end pivotally connected by a rod 168 to a diaphragm 170 that divides a casing 172 into two expandable chambers 174 and 176. Chamber 174 is connected by conduits 178, 126 and 26 to vent ring 24, while chamber 176 is connected by conduits 180 and 182 to a temperature responsive device 184, and is also connected by conduits 180 and 186 to the main air passage 17 below throttle 16. In chamber 176 is a spring 188 which biases diaphragm 170 to the right, in opposition pressure differential between the impact air pressure in chamber 174

and the air pressure in the air passage 17 below throttle 16, which is transmitted by conduits 186 and 180 to chamber 176.

The temperature responsive device 184 comprises a casing 196 having a transverse partition 192, provided with a port 194. The left end of casing 196 is vented to the atmosphere through a conduit 197. Fixed to the left end of casing 196 is an exteriorly threaded sleeve 198 which is threaded into a socket in a cylinder head 200 of the engine. Fixedly attached to the interior of sleeve 198 is a rod 202 which terminates at its right end in a contoured valve 204, adapted to vary the opening through port 194. Rod 202 is made of a material having a much smaller coefficient of thermal expansion than sleeve 198, so that as the sleeve and rod are heated by heat from engine cylinder head 200, sleeve 198 expands at a greater rate than rod 202 and withdraws the valve 204 from port 194, thus increasing the opening of said port. Conversely, a lowering of the temperature of the engine cylinder head 200 causes a corresponding closure in port 194.

As the aircraft gains altitude and the barometric pressure of the atmosphere decreases, a greater throttle opening is required to maintain the same engine speed, hence the pressure drop across the throttle decreases with increasing altitude. Since the pressure differential acting on diaphragm 170 varies directly with the pressure drop across throttle 16, it follows that said pressure differential will decrease with increasing altitude. As said pressure differential decreases the thrust on spring 156 which causes valve 146 to move to left, it reduces the opening of port 150. This results in a decrease in the pressure differential $p_2 - p_3$ and a corresponding decrease in idle fuel flow to the engine, as described hereinabove, and indicated by line C in Figure 3. Conversely, an increase in the pressure differential acting on diaphragm 170 results in an increase in idle fuel flow to the engine; so that the idle mixture is varied inversely with altitude and directly with barometric pressure.

If it should be desired to vary the idle fuel flow in the opposite manner, i. e., directly with altitude and inversely with barometric pressure, this result can be obtained by simply connecting conduit 178 to chamber 176, and conduit 180 to chamber 174, and moving spring 188 to chamber 174 so as to oppose the reversed direction of the pressure differential acting on diaphragm 170.

As the cylinder head temperature of the engine increases, the length of sleeve 198 increases more than the length of rod 202, which causes valve 204, to increase the opening of port 194, thus permitting atmospheric air to bleed into chamber 176 and increase the pressure therein. The amount of this increase of pressure in chamber 176 depends also upon the relative sizes of the restrictions in conduits 180, 182 and 186; the larger the size of restriction in 182 as compared with that in 186, the greater the increase in pressure in chamber 176 for any given opening of port 194, and vice versa. The restriction in conduits 180 and 186 also retard the transmission to chamber 176 of any sudden fluctuations of pressure in the main air passage 17, below throttle 16.

Conversely, a decrease in temperature of engine cylinder head 200 decreases the pressure in chamber 176 and thus increases the pressure differential acting on diaphragm 170. And since, as shown above, any increase in the pressure differential acting on the diaphragm 170 causes a corresponding increase in idle fuel flow (and vice versa), it follows that the idle mixture ratio is varied inversely with engine cylinder head temperature. If it should be desired to vary the idle fuel flow in the opposite direction, i. e., directly with engine cylinder head temperature, this result can be obtained by simply reversing the arrangement of sleeve 198 and rod 202, so that valve 204 would close port 194, with increasing temperature of the engine cylinder head. To this end rod 202 would be made of material having a higher coefficient of thermal expansion than that of the material of sleeve 198.

From what has been shown above, it is clear that the carburetor illustrated in Figure 2, operates in the same manner as the carburetor of Figure 1, except that the additional elements incorporated in Figure 2 modify the action of the idle fuel pressure regulating valve mechanism 130, so as to vary the idle fuel mixture with barometric pressure (altitude) and engine cylinder head temperature, in a selected manner in order to meet the requirement of optimum engine performance in the idling range of operation.

While I have shown and described the preferred embodiments of my invention, I desire it to be understood that I do not limit myself to the precise details of construction disclosed by way of illustration, as these may be changed and modified by those skilled in the art without departing from the spirit of my invention or exceeding the scope of the appended claims.

I claim:

1. A carburetor for an internal combustion engine, comprising: an air supply throttle; means for supplying to said engine air and liquid fuel in selected mixture proportions throughout the operating range of said engine above its idling range, including a metering orifice, for metering said fuel supply in selected proportion to the rate of said air supply during said operating range; means, unaffected by variations in the rate of air supply, for supplying fuel to said engine throughout its idling range, under a selected variable metering head which is governed by the pressure drop across said orifice and which causes said idle fuel to flow at such rates as to form an idling mixture of selected varied proportions richer than said operating range mixture proportions; and means for modifying said idling rates of fuel flow in accordance with the pressure drop across said throttle.
2. A carburetor for an internal combustion engine, comprising: an air supply throttle; means for supplying to said engine air and liquid fuel in selected mixture proportions throughout the operating range of said engine above its idling range, including a metering orifice, for metering said fuel supply in selected proportion to the rate of said air supply during said operating range; means, unaffected by variations in the rate of air supply, for supplying fuel to said engine throughout its idling range, under a selected variable metering head which is governed by the pressure drop across said orifice and which causes said idle fuel to flow at such rates as to form an idling mixture of selected varied proportions richer than said operating range mixture proportions; and means for modifying said idling rates of fuel flow in accordance with the pressure drop across said throttle.
3. A carburetor for an internal combustion engine, comprising: an air supply throttle; means for supplying to said engine air and liquid fuel in selected mixture proportions throughout the operating range of said engine above its idling range, including a metering orifice, for metering said fuel supply in selected proportion to the rate of said air supply during said operating range; means, unaffected by variations in the rate of air supply, for supplying fuel to said engine throughout its idling range, under a selected variable metering head which is governed by the pressure drop across said orifice and which causes said idle fuel to flow at such rates as to form an idling mixture of selected varied proportions richer than said operating range mixture proportions; and means for modifying said idling rates of fuel flow in accordance with engine temperature.
4. A carburetor for an internal combustion engine, comprising: an air supply throttle; means for supplying to said engine air and liquid fuel in selected variable proportions throughout the operating range of said engine above its idling range, including a main fuel flow regulating valve, responsive to the relative rates of said air and fuel supplies, and an idle fuel pressure regulating valve, separate from but acting co-ordinately with the action of said main valve, for supplying idling fuel to said engine

under a variable metering head such that its flow rate decreases from a maximum at lowest idling speed to a minimum in idling mid-range, and then increases during the remainder of said idling range; and means for modifying the action of said idle fuel pressure regulating valve in accordance with the pressure drop across said throttle.

5. A carburetor for an internal combustion engine, comprising: an air supply throttle; means for supplying to said engine air and liquid fuel in selected variable proportions throughout the operating range of said engine above its idling range, including a main fuel flow regulating valve, responsive to the relative rates of said air and fuel supplies, and an idle fuel pressure regulating valve, separate from but acting co-ordinately with the action of said main valve, for supplying idling fuel to said engine under a variable metering head such that its flow rate decreases from a maximum at lowest idling speed to a minimum in idling mid-range, and then increases during the remainder of said idling range; and means for modifying the action of said idle fuel pressure regulating valve in accordance with engine temperature.

6. A carburetor for an internal combustion engine, comprising: an air supply throttle; means for supplying to said engine air and liquid fuel in selected variable proportions throughout the operating range of said engine above its idling range, including a main fuel flow regulating valve, responsive to the relative rates of said air and fuel supplies, and an idle fuel pressure regulating valve, separate from but acting co-ordinately with the action of said main valve, for supplying idling fuel to said engine under a variable metering head such that its flow rate decreases from a maximum at lowest idling speed to a minimum in idling mid-range, and then increases during the remainder of said idling range; and means for modifying the action of said idle fuel pressure regulating valve in accordance with barometric pressure and engine temperature.

7. A carburetor for an internal combustion engine, comprising: an air supply throttle; means for supplying

to said engine air and liquid fuel in selected variable proportions throughout the operating range of said engine above its idling range, including a main fuel flow regulating valve, responsive to the relative rates of said air and fuel supplies, and an idle fuel pressure regulating valve, separate from but acting co-ordinately with the action of said main valve, for supplying idling fuel to said engine under a variable metering head such that its flow rate decreases from a maximum at lowest idling speed to a minimum in idling mid-range, and then increases during the remainder of said idling range; and means, responsive to engine temperature, for modifying the action of said idle fuel pressure regulating valve in accordance with said temperature.

15 8. A carburetor for an internal combustion engine, comprising: an air supply throttle; means for supplying to said engine air and liquid fuel in selected variable proportions throughout the operating range of said engine above its idling range, including a main fuel flow regulating valve, responsive to the relative rates of said air and fuel supplies, and an idle fuel pressure regulating valve, separate from but acting co-ordinately with the action of said main valve, for supplying idling fuel to said engine under a variable metering head such that its flow rate decreases from a maximum at lowest idling speed to a minimum in idling mid-range, and then increases during the remainder of said idling range; and means, responsive to engine temperature, for modifying the action of said idle fuel pressure regulating valve in accordance with said temperature.

20 9. A carburetor for an internal combustion engine, comprising: an air supply throttle; means for supplying to said engine air and liquid fuel in selected variable proportions throughout the operating range of said engine above its idling range, including a main fuel flow regulating valve, responsive to the relative rates of said air and fuel supplies, and an idle fuel pressure regulating valve, separate from but acting co-ordinately with the action of said main valve, for supplying idling fuel to said engine under a variable metering head such that its flow rate decreases from a maximum at lowest idling speed to a minimum in idling mid-range, and then increases during the remainder of said idling range; a valve, responsive to engine temperature, and a valve, responsive to barometric pressure, for modifying the action of said idle fuel pressure regulating valve in accordance with variations in said temperature and barometric pressure.
